Miles F. YOUNT Inventor

By

Hardway Tatting Attorneys

UNITED STATES PATENT OFFICE.

MILES F. YOUNT, OF BEAUMONT, TEXAS.

TONGS.

Application filed August 13, 1923. Serial No. 657,028.

To all whom it may concern:

Be it known that I, MILES F. YOUNT, a citizen of the United States, residing at Beaumont, in the county of Jefferson and State 5 of Texas, have invented certain new and useful Improvements in Tongs, of which the following is a specification.

This invention relates to new and useful improvements in a tong, and has particular 10 relation to a novel type of latch, by means of which the tong jaws may be secured around the pipe or tool joint, or other round object to be turned.

One object of the invention resides in the 15 provision of a tong latch which may be adjusted so as to take up the wear of the tong parts to insure a proper, and engaging fit, of the jaws around the pipe or tool joint or other object to be turned.

20 A further feature of the invention resides in the provision of a latch having a suitable hand grip, by means of which it may be manipulated with safety to the operator.

With the above and other objects in view, 25 the invention has particular relation to certain novel features of construction, operation, and arrangement of parts, an example of which is given in this specification and illustrated in the accompanying drawings, 30 wherein:—

Figure 1 shows an assembled view of the tong equipped with my improved type of latch, and shown in open position to receive the pipe or other object to be turned.

35 Figure 2 shows a plan view of the latch; and,

Figure 3 shows a side view thereof.

In the drawings, the numeral 1 designates the tong handle. The tong in use is usually 40 held suspended in the derrick by means of a suitable cable 2 so that the same will be at all times in position for easy application to, or disengagement from, the pipe. The numeral 3 designates an accurate jaw, one end of 45 which is slotted to receive the inner end of the handle which is pivoted therein, and the other end of this jaw 3 has the latch, herein-after described, pivoted thereto. The numeral 4 designates the other tong jaw which 50 is pivotally connected to the handle, through the upper and lower connecting links 5, 5. These links are pivoted at one end to the handle, a short distance back from the inner end thereof, and at their other ends they are

pivoted to the inner end of the jaw 4. The 55 other end of the jaw 4 is provided with an outwardly projecting catch 6.

The latch is composed of the side bars 7, 7, and the latch block 8, which is adjustably secured, as hereinafter stated, on the outer 60 ends of said bars. These bars are pivoted to the outer end of the jaw 3, on opposite sides thereof, by means of suitable bearing pin 9. The latch block 8 has end bearings through which the outer ends of the side bars are 65 fitted, and said ends are outwardly threaded to receive the adjusting nuts 10, 10, and the clamp nuts 11, 11. The adjusting nuts 10 are first threaded onto the respective bars 7, and the latch block is then fitted onto the 70 outer ends of said bars, and the nuts 11 then secured in place to secure said block against detachment. The inner side of the 75 respective ends of said block are shouldered in, as shown in Figure 3, so that said inner side will fit in between said adjusting nuts, and lock them against turning. The outer side of the latch block 8 has a suitable hand grip 12, by means of which the latch may be manipulated.

80 The jaws, when fitted around the pipe or tool joint, are locked in position by swinging the latch over the catch 6, said latch block engaging with said catch, and securing the jaws in position. In case the parts 85 become worn, or if for any reason the jaws do not grip the pipe closely enough, the lock nuts may be removed and the latch block taken off, and the nuts 10 adjusted to the proper place and the parts again assembled, 90 and the latch thus may be adjusted until a proper adjustment is secured. In order to release the tongs from the pipe, the grip may be grasped and the latch released from the catch 6, and the jaws then swung into open 95 position.

As before stated, the tong is suspended by the cable 2, and it is desirable that the tong always maintain a horizontal position in applying the same to the pipe. If the latch 100 is permitted to swing around too far, when in open position, it will cause the tong to swing diagonally and out of a horizontal plane. To prevent this I have provided a shoulder 13 at the hinged end of the latch 105 on the outside, which contacts against the jaw 3, and limits the outward movement of the latch, so as to hold it in approximately a

straight line position with the handle when open, thus causing the tong to swing in approximately a horizontal position.

What I claim is:

- 5 1. A tong latch including side bars, and an adjustable latch block mounted on said bars at one end thereof.
- 10 2. The combination with a tong having a handle and a pair of engaging jaws attached to one end thereof, of a latch including side bars pivoted at one end to the free end of one jaw, an engaging member adjustably mounted on the other ends of said bars, and adapted to engage with the other jaw.
- 15 3. The combination with a tong having a handle and a pair of engaging jaws attached to one end thereof, of a latch including side bars pivoted at one end to the free end of one jaw, an engaging member having end bearings, adjustable on the other ends of said bars, and adapted to engage with the other jaw, and a hand grip carried by said engaging member.
- 20 4. The combination with a tong having a handle, and a pair of arcuate engaging jaws, connected at one end to one end of said handle and a catch carried by the free end of one of said jaws, of a latch including a pair of side bars pivoted, at one end, to the free end of the other jaw, an engaging member having end bearings adjustable on the other ends of the bars, said engaging member being adapted to engage over said catch to secure the free ends of said jaws together.

5. The combination with a tong having a handle, and a pair of arcuate engaging jaws, connected at one end to one end of said handle, and a catch carried by the free end of one of said jaws, of a latch including a pair of side bars pivoted, at one end, to the free end of the other jaw, an engaging block formed with end bearings adjustable on the other ends of the bars, said block being adapted to engage over said catch to secure the free ends of said jaws together, and an abutment carried by the latch and located to abut against the jaw, carrying the latch, to limit the outward movement of said latch.

6. A latch including side bars, a latch block having end bearings through which corresponding ends of the side bars are fitted, and adjustable means securing said block on said bars.

7. A latch including side bars each outwardly threaded at one end, a latch block having end bearings through which the threaded ends of the side bars are fitted, nuts threaded onto said ends of said bars on opposite sides of said block, one side of said block being recessed at each end to receive the adjacent nuts.

In testimony whereof I have signed my name to this specification in the presence of two subscribing witnesses.

MILES F. YOUNT.
